CONSIN.

CUTTER HEAD.

1,413,665.

Specification of Letters Patent. Patented Apr. 25, 1922.

Application filed March 31, 1919, Serial No. 286,282. Renewed March 8, 1920. Serial No. 364,247.

To all whom it may concern:

Be it known that we, FRANKLIN L. LANE and FRANK R. WEAVER, citizens of the United States, residing at Beloit, in the 5 county of Rock and State of Wisconsin, have invented certain new and useful Improvements in Cutter Heads, of which the following is a specification.

This invention relates to wood-working 10 machinery and to cutter heads of the type disclosed in our co-pending application Serial No. 184,187, and has particular reference to the provision of a peculiarly efficient mounting for the peripheral tools of a cutter 15 head, although adaptable for use in the mounting of the tools upon a side face.

In order that the invention may be readily understood by those skilled in the art, a preferred embodiment of the same is set forth 20 in the accompanying drawings and in the description based thereon. As, however, the invention is susceptible of embodiment in other and varied constructional forms depending upon the material and the nature of 25 the work to be performed, the drawing and description are to be taken in an illustrative and not in an unnecessarily limiting sense. In the drawings—

Fig. 1 is a fragmentary side elevation of a 30 cutter head adapted to the mounting of the invention;

Fig. 2 is a fragmentary section in the plane 35 of the cutter head taken through the mounting of the invention;

Fig. 3 is an edge view of Fig. 2 from the position indicated by the lines 3—3; and

Fig. 4 is a detail perspective view of the gib employed.

Having particular reference to the drawing, the cutter head 11 is herein shown as provided in its side face with the same provision for mounting the side cutting tools shown in our co-pending application above referred to, not necessary of description here 45 and merely indicated generally by the reference numeral 12. For the mounting of peripheral tools, herein shown as cutting knives and indicated by the reference numeral 13, the edge face of the cutter head is 50 provided with a slot 14 which is preferably disposed at an oblique angle to the radius of the head or to the face thereof and also at an oblique angle to the plane of rotation of the head. This slot extends for a limited dis-

tance below the surface and is intended for 55 the reception of the tool 13 and for the gib 15. As the gib is not always employed, the tool and gib may be considered for practical purposes in interpreting certain of the claims as an entity or as a unitary element, 60 it being obvious that the making of the two in separate parts rather than in one is dictated by convenience and economy, renewal, sharpening, etc. They cooperate as one piece with the clamping devices hereinafter to be 65 described.

Alongside the slot 14 and substantially parallel therewith is a preferably cylindrical bore 16, one curved side of which cuts the slot 14. This bore 16 extends somewhat 70 deeper than the slot 14 and may be provided with the conical bottom portion 17.

The second preferably cylindrical bore 18 is provided in the cutter head perpendicular to and intersecting the bore 16 or equivalently connected therewith by the restricted continuation of the bore 16 represented at 16^a.

Within the bore 18 is seated a preferably cylindrical angularly adjustable plug or 80 seat member 19 provided with a transverse aperture 20 which is interiorly screw threaded. Within the bore 16 is mounted a screw plug 21 having its threaded portion entering the threaded aperture 20 of the 85 plug 19 and provided with a squared head for operation by means of a wrench or similar tool. Rotatably disposed upon the screw plug 21 is a collar 22 cut away at one side to provide a wedge face 23 for co-operation with a similar beveled wedge face 24 of the gib 15. The screw bolt 21 is provided with a shouldered portion 25 bearing 90 downwardly upon the collar 22 and the gib 15 is provided with positioning portions 26 95 providing therebetween a recessed portion 27 within which the collar plays. The ends of the gib 15 or, when used in connection with a tool 13 arranged obliquely to the plane of rotation, that end of the gib adjacent the leading end of the tool 13 is recessed or cut away at 28 to provide clearance space for the chips, cooperating in this regard with the recessed portion 29 on the side face of the cutter head.

It is a common experience that when the cutter head and its tool mountings have been in use for some time the threaded connection

between the adjusting set screws and the cutter head become worn and inefficient; also that bits of metal or wood or other foreign matter drop into the threaded aperture for the bolt and prevent proper seating of the set screw and, becoming jammed therein, are difficult of removal; also the laying out of the slot, the threaded bores for the set screw, the beveled coating surfaces of the set screws and gibs or tools, and other co-operating constructional features, if faulty in any respect, result in an inaccurate bearing of the one part upon another and consequent impairment of the mounting. To guard against such difficulties and to render innocuous slight irregularities in construction, has been an important consideration in the devising of the present mounting. It will be observed that providing a threaded plug 18 for cooperation with the screw bolt 21 enables such threaded plug to be renewed as often as may be desired in order to preserve its threads in perfect condition; also that by removing the plug 18 temporarily it may be cleared of any dirt which may collect therein; also that by reason of its rotatable disposition within the cutter head 11 the screw plug serves in effect as a pivotal or hinge mounting for the screw plug 21 which is thus given a slight lateral play within its bore 16 in order to accommodate itself to any irregularities in the co-operating wedge-bearing surfaces between itself and the gib 15. The difficulty of tapping the bottom of a deep bore within the cutter head is obviated, the general construction is simplified and rendered practically immune from carelessness and inaccuracies on the part of workmen.

40. We claim:

1. A tool mounting comprising a cutter head provided with a slot opening to a working face thereof, a bore at one side of the slot, and a second bore transversely intersecting the first bore, a removable member disposed within the slot, a screw plug rotatably mounted in the first bore, an angularly adjustable plug disposed within the second bore with its axis extending transversely of the screw plug and provided transversely of its axis with an interiorly threaded aperture for cooperation with the screw plug, the screw plug and removable member having cooperating wedge surfaces.

55. 2. A tool mounting comprising a cutter head provided with a tool-receiving slot opening to a working face thereof, a bore parallel to the slot and cutting the marginal portion thereof, and a second bore transversely intersecting the first bore, a tool disposed within the slot, a gib alongside of and bearing on the tool, a screw plug arranged for angular movement in the first bore, a sleeve rotatable on the screw plug, and an angularly adjustable plug disposed

within the second bore and provided transversely of its axis with an interiorly threaded aperture for cooperation with the screw plug, the sleeve of the screw plug and the gib having cooperating wedge surfaces. 70

3. A tool mounting comprising a cutter head provided with a slot opening to a working face thereof and at an oblique angle to said face and to the plane of rotation of the head, a bore at one side of the slot and cutting the marginal portion thereof, and a second bore intersecting the first bore transversely, a removable member disposed within the slot, a screw plug in the first bore, a seat member rotatably retained within the second bore and provided transversely of its axis with an interiorly threaded aperture for reception of the screw plug, the screw plug and removable member having cooperating wedge surfaces. 80 85

4. A tool mounting comprising a cutter head provided with a slot opening to a working face thereof and at an oblique angle to said face and to the plane of rotation of the head, a bore at one side of the slot and cutting the marginal portion thereof, and a second bore intersecting the first bore transversely, a tool disposed within the slot, a gib alongside of and bearing on the tool, a screw plug in the first bore, a sleeve rotatable upon the screw plug, a plug rotatably mounted within the second bore and provided transversely of its axis with an interiorly threaded aperture for the reception of the screw plug, the sleeve and the gib having cooperating wedge surfaces. 90 95

5. A tool mounting comprising a cutter head provided with a tool-receiving slot opening to its peripheral working face, a bore at one side of the slot and cutting the marginal portion thereof, and a second bore transversely intersecting the first bore, the first bore opening to the periphery of the tool head and the second bore opening to the side face thereof, a tool disposed within the slot, a rotatable screw plug in the first bore, an angularly adjustable plug disposed within the second bore and provided transversely of its axis with an interiorly threaded aperture for the reception of the screw plug, and wedge elements interposed between the screw plug and tool whereby the thrust of the screw plug is transmitted to the tool as a clamping action. 105 110 115

6. A tool mounting comprising a cutter head provided with a tool-receiving slot opening to its peripheral working face, and at an oblique angle to the peripheral face and also to the plane of rotation of the head, a bore at one side of the slot and cutting the marginal portion thereof, and a second bore intersecting the first bore, the first bore open to the peripheral edge of the cutter head and the second bore open to the side face thereof, a tool disposed within the slot, a gib 120 125 130

alongside of and bearing on the tool and having an oblique face, a screw plug movable longitudinally and angularly in the first bore, a sleeve rotatable on the screw head and having lateral bearing on the wall of said bore and an oblique face cooperating with that of the gib, an angularly adjustable plug disposed within the second bore and provided transversely of its axis with an interiorly threaded aperture for the reception of the screw plug.

7. A tool mounting comprising a cutter head provided with a tool-receiving slot opening to a working face thereof, a bore 15 extending into the cutter head in a general radial direction adjacent the tool-receiving slot, and a second bore intersecting the first bore, a removable member disposed within the slot, a screw plug movable angularly and longitudinally in the first bore, a seat member 20 movably retained within the second bore and provided with an interiorly threaded aperture for the reception of the screw plug, said seat member being movable about an axis which is transverse of the axis of the 25 screw plug, the screw plug and removable member having engaging faces whereby the

thrust of the former is utilized to clamp the latter in place.

8. A tool mounting comprising a cutter head provided with a bore extending into said head in a general radial direction and a second bore intersecting the first bore, a screw plug movable angularly in the first bore and operable from the peripheral side 30 of the head, a seat member retained within the second bore and having adjustable engagement with the screw plug, said seat member being movable to accommodate angular movement of the screw plug, a tool carried by the head, and wedge elements interposed between the screw plug and tool and having lateral bearing against a portion of the head whereby the thrust of the screw plug is utilized to exert a clamping action 35 upon the tool.

In testimony whereof we have hereunto signed our names in the presence of two subscribing witnesses.
